UNITED STATES PATENT OFFICE.

HAROLD K. FOX, OF FRESNO, AND GEORGE J. FISHER, OF BIG CREEK, CALIFORNIA.

CONCRETE-MIXING MACHINE.

Application filed March 27, 1922. Serial No. 547,115.

To all whom it may concern:

Be it known that we, HAROLD K. FOX and GEORGE J. FISHER, citizens of the United States, residing in Fresno, county of Fresno,

5 State of California, and Big Creek, county of Fresno, State of California, respectively, have jointly invented new and useful Improvements in Concrete-Mixing Machines, of which the following is a specification.

10 This invention relates to a machine for mixing and delivering concrete, or the like, and it is an object of the invention to provide a machine of this general character which is simple, effective, and easily operated.

15 The machine provided by the present invention is particularly adapted for use in mixing and placing concrete tunnel linings, etc., although, we do not wish it understood that the machine is limited in any way to

20 use in connection with any particular class of work as it is obvious that it may be advantageously employed in practically any situation where concrete, or the like, is being used.

25 A noteworthy feature of the invention is the general arrangement and construction of the machine. The construction and arrangement is such that the machine is extremely simple to operate, is compact, and is particularly effective. This makes it particularly applicable to use in tunnels, and the like, where space is limited.

30 Another noteworthy feature of the invention is the manner in which the air, which operates the closure of the mixing drum, also aids the air jet of the ejector in driving the concrete through the discharge conduits. This feature makes the machine particularly effective and efficient.

35 40 The various objects and features of the invention will be best and more fully understood from the following detailed description of a typical preferred embodiment of the invention throughout which reference is had to the accompanying drawings in which—

45 Fig. 1 is a side elevation of the complete machine showing the mixing drum down, or in its mixing position; Fig. 2 is a detailed sectional view of the mixing drum and the ejector being a view showing the relative positioning of the drum and ejector and showing the manner in which the drum and ejector are connected; Fig. 3 is a plan view 50 of the machine; Fig. 4 is a transverse detailed sectional view of the machine, be-

ing a view taken as indicated by line 4—4 on Fig. 3 and Fig. 5 is a detailed transverse sectional view of the machine being a view taken as indicated by line 5—5 on Fig. 1.

55 The machine provided by the present invention comprises, generally, a frame 10, a mixing drum 11 rotatably and pivotally carried in the frame 10 by a carriage 12, power means 13 for rotating the drum 11, means 14 for swinging the drum 11 about its axis of pivotal mounting, a pneumatic ejector 15, and a connector 16 between the drum 11 and ejector 15 whereby the material mixed by the drum is delivered to the ejector. The drum 11 may be, and in fact preferably is, of the general design and formation of drums ordinarily used in concrete mixers, and the like. For instance, the drum may be tapered from one end to the other so that it is considerably larger in diameter at one end than at the other, and may be formed at its large end with an intake opening 18 and at its small end with a discharge or outlet opening 19. The particular drum which I have illustrated in the drawings comprises an end casting 20 which forms the large end of the drum, an end casting 21 which forms the small end of the drum, and sheet metal parts 22 which are connected together and to the castings 20 and 21 to form the middle or body portion of the drum. The intake opening 18 and outlet opening 19 are formed concentrically in the castings 20 and 21, respectively. The casting 20 is formed with a concentric bearing part 23 adapted to be engaged by supporting rollers, as hereinafter described, and is formed with a concentric part 24 which carries a toothed band or gear 25. The casting 21 has a concentric trunnion part 26 which is rotatably carried in a bearing 27 of the carriage 12, and is provided with a shoulder 28 which engages the end of the bearing 27 so that the end thrust of the drum is borne by the bearing 27. A recess 28 is formed in the outer end of the bearing 27 to carry packing 29. A plate 30 is secured to the end of the bearing 27 by bolts 31 and is formed with a projection 32 which extends into the recess 28 to bear against the packing 29 so that the packing is maintained in pressure engagement with the trunnion part 26 of the casting 21. The packing 29 prevents air from

80 85 90 95 100 105 110 escaping from the machine between the trunnion part 26 and bearing 27 and pre-

vents the materials which are being handled by the machine from getting between the trunnion part 26 and bearing 27 to injure the bearing surfaces.

5 The connector 16 is, in accordance with the preferred form of the invention, in the form of an elbow having one end secured to the plate 30 so that its opening registers with the outlet opening 19 of the drum, and having the other end facing horizontally toward one side of the machine, as clearly illustrated throughout the drawings. The connection between the connector 16 and plate 30 is tight so that no air can escape 10 from the machine at that point. Within the drum 11, for instance, on the inner surface of one of the sheet metal parts 22, we provide vanes 35 which, when the drum is rotated, act to mix the material and to feed it 15 toward the outlet or small end.

20 The present invention provides a closure or cover plate 36 for the intake opening 18 of the drum 11. The plate 36 is within the drum and is somewhat larger than the opening 18 so that its periphery portion engages the inner surface of the end casting 20 when it is in position to close the opening 18, as clearly shown in Fig. 2 of the drawings. The cover plate 36 may be supported and 25 guided by pins 37 extending outwardly from it through guide openings 38 in the end casting 20. In accordance with the invention a hollow stem 40 extends from the plate 36 inwardly in the drum 11 and slidably fits into 30 the outer end portion of an air pipe 41. The air pipe 41 passes through a packing gland 42 in the connector 16, passes through the outlet opening 19 of the drum 11, and extends a considerable distance into the body 35 portion of the drum, as clearly shown in Fig. 2 of the drawings. At a suitable point outside of the packing gland 42 the air pipe 41 is connected with an air supply pipe 43 and an air exhaust pipe 44 by a three-way 40 valve 45. There is preferably a flexible connection 41a between the pipe 41 and valve 45 to allow more or less movement between the pipe and valve and its connected parts, the pipes 43 and 44. The three-way valve 45 45 can be manipulated to allow air from the supply pipe 43 to enter the air pipe 41, or to allow air from the pipe 41 to escape or exhaust through the exhaust pipe 44. When air from the supply pipe 42 is allowed to 50 enter the pipe 41 it flows into the hollow stem 40 which extends from the plate 36 and moves the plate outwardly until it engages the inner surface of the casting 20 or in other words to the position where it closes 55 the intake opening 18. Ports 47 are provided in the stem 40 at a point where they will be just out of the air pipe 41, when the plate 36 is in position to close the opening 18, allowing air from pipe 41 to escape into 60 the drum 11. The present invention pro-

vides means, preferably in the form of a spring, for moving the plate 36 away from the casting 20 to open the opening 18 when the pressure within the pipe 41 and drum 11 is released, as by manipulating the valve 45 70 to close the connection between the supply pipe 43 and the pipe 41 and open the connection between the pipe 41 and the exhaust pipe 44. In the particular form of the invention illustrated in the drawings a tension 75 spring 48 is carried on the stem 40 and end portion of pipe 41 between the plate 36 and a collar 49 on the pipe 41 so that it moves the plate 36 away from the casting 20 as soon as the air pressure is released. 80

85 The carriage 12 comprises two side parts 50 which are pivotally connected to the side parts 51 of the main frame 10 on a common axis by pivotal bolts 52, on which are guided the guide parts 75 of the frame 10. The guide parts extend upwardly from the side parts 51 of the frame 10 so that the outer end portion of the carriage is between them and is guided in its swinging movement. The inner or pivoted ends of the side parts 90 50 of the carriage are connected by a cross part 53 at the center of which is the bearing 27, which carries the trunnion part 26 of the drum 11. The free or outer ends of the side parts 50 are connected by a yoke or U-shaped frame 54 in which is mounted a plurality of rollers 55 which engage the concentric bearing part 23 of the drum to rotatably support the large end of the drum in the carriage. The various parts of the machine are arranged and proportioned so that the drum 11 is rotatably supported in the carriage 12 by the bearing 27 and U-shaped frame part 54 so that the outlet end part of the connector 16 is concentric with the axis of the pivot 95 bolts 52. 100

105 The power means 13 provided for rotating the drum 11 is, in accordance with the preferred form of the invention, mounted on the carriage 12 so that it and the drum 11 can be swung about the axis of the pivot bolts 52 as a unit without in any way interfering with the drive of the drum. The power means 13 may be an electric motor 60 mounted on a convenient part of the carriage 110 50 so that it will drive a shaft 61 which carries a pinion 62 that meshes with the gear 25, as clearly illustrated throughout the drawings. In practice it is usually desirable to provide a speed reduction mechanism 53 between the motor 60 and shaft 61 so that the drum 11 will not be driven too fast. 115

120 The means 14 which we have illustrated in the drawings for operating or swinging the carriage 12 about its axis of pivotal connection with the main frame 10, comprises two pneumatic jacks 70 connected by pipes 71 so that they are controlled by a single valve 72. The jacks are mounted on the frame 10 and are connected with the outer ends of the side 125 130

parts 50 and the carriage by chains 73, which connect to the ends of the side parts 50 and extend over pulleys 74 mounted on the upper ends of the guide parts 75 of the frame 10, and cables 76 which connect to the chains 73, extend around pulleys 78 at the lower ends of the guide parts 75 and connect with the piston rods 77 of the jacks 70. From inspection of the drawings, and particularly Fig. 1 of the drawings, it will be obvious how the jacks 70 may be operated to cause the carrier 12 to be swung from a position such as is shown in Fig. 1 to a position where its outer end is between the upper end portions of the guide parts 75 and the center line or axis of the drum 11 is in a position such as is indicated by the dotted line A in Fig. 1.

The ejector 15, which may be a stationary part, comprises a conduit 80, which connects to, and receives concrete from, the connector 16, and an air nozzle 81 which extends into the conduit 80 so that it directs a jet of air into the conduit 80 to draw material into the conduit 80 from the drum 11 through the connector 16 and discharges it from the conduit 80 into a distributing pipe 81 which carries it to the point where it is to be used. The conduit 80 is preferably, although not necessarily, in the form of an elbow and the nozzle 81 is directed toward the distributing pipe 81. A suitable control valve 84 is arranged in connection with the nozzle 81 so that the jet of air can be regulated. When the ejector 15 is stationary with the frame 10 it is necessary that the connection between the ejector and connector 16 be such as to allow the connector to turn relative to it when the carriage 50 is swung about its axis of pivotal connection with the frame 10. The connection or joint which we have illustrated in the drawings comprises a coupling part 90 and two rings 91, one secured to each of the connected parts, that is, one secured to the connector 16 and one to the conduit 80, the rings 91 being screw threaded on the ends of the couplings. This arrangement and construction provides a very simple, yet effective flexible joint which will allow the necessary turning movement between the connected parts.

When operation of the machine is started the carrier 50 is in the down position so that the drum 11 is substantially horizontal, the power means 13 is thrown into operation so that the drum 11 is constantly rotated, the three-way valve 45 is positioned so that there is no pressure in the air pipe 41 thus allowing the spring 48 to hold the plate 36 away from the end casting 20 so that the intake opening 18 is open, and the rock, sand, cement, water, etc., or whatever other ingredients are to be mixed, are emptied into the drum through the opening 18. When the batch of material is in the drum 11 the three-

way valve 45 is manipulated so that air from the air supply pipe 45 enters the pipe 41 and forces the plate 35 into its closed position whereupon a part of the air escapes through the ports 47 so that some pressure builds up in the drum 11 and so that there is a flow of air out of the drum through the connector 16 and conduit 80 of the ejector. The continuous rotation of the drum causes the materials to be effectively mixed, the vanes 35 acting to more or less churn the materials to intimately mix them. When the materials are mixed, or when the concrete has been formed, the ejector having been put into operation by opening the valve 46, the jacks 70 are operated by opening the valve 72 so that the carriage 50 is moved to its upper position causing the drum 11 to assume a tilted position which causes the concrete in it to discharge through the outlet opening 19 and connector 16 into the ejector which effectively forces it out through the distributing pipe 81. When the drum 11 is tilted the vanes 35 are effective in feeding the concrete toward the small end of the drum and therefore out through the opening 19, and the flow of air from the drum 11 through the opening 19 and connector 16 operates to aid the action of the ejector. When the batch of concrete has been discharged the air is released from the jacks 70 allowing the carrier 12 to move by gravity to its lower position. It will be obvious, of course, how the distributing pipe 81 may be of such size and length as to properly conduct the concrete to the point where it is to be used. From the foregoing description it will be noted that the machine is simple in operation, compact, and it will be obvious how it can be very advantageously operated in tunnels, and the like, where space is limited and where compressed air and electricity are the most advantageous mediums for operating such machinery.

Having described only a typical preferred form of our invention we do not wish to limit ourselves to the particular details hereinabove set forth but wish to reserve to ourselves any changes and variations that may appear to those skilled in the art or that may fall in the scope of the following claims.

Having described a preferred form of our invention, we claim:

1. In a machine of the character described, a mixing mechanism adapted to be tilted to discharge material mixed by it, a stationary ejector adapted to handle material mixed by the mixing mechanism, and a flexible connection between the mixing mechanism and the ejector.

2. In a machine of the character described, a mixing drum, a tilting carrier for the drum adapted to normally hold the carrier in a substantially horizontal position and adapted to be tilted to discharge material mixed by it, a stationary ejector, and a connection

between the drum and ejector to receive material from the drum and deliver it to the ejector.

3. In a machine of the character described, a rotatable mixing drum having a discharge opening at one end and adapted to be tilted to discharge material through the opening, a connector having an intake end connected with said opening so that it receives material from the opening and so that the drum is free to rotate relative to the connector and having a discharge end concentric with the axis about which the drum is adapted to tilt, and an ejector connected with the discharge end of the connector to receive material therefrom and so that the connector can rotate relative to the ejector.

4. In a machine of the character described, a mixing drum having an inlet opening and an outlet opening, a closure for the inlet opening, and pneumatic means for actuating the closure, said means discharging air into the drum when the closure is in position to close the opening.

5. In a machine of the character described, a rotatable mixing drum having an outlet opening, a pneumatic ejector connected with said opening to receive material from the drum, and means for supplying air to the drum so that it will flow to the ejector with the material.

6. In a machine of the character described, a mixing drum having an inlet opening and an outlet opening, a pneumatic ejector connected with the outlet opening to receive material from the drum, a closure for the inlet opening, and pneumatic means for actuating the closure, said means discharging air into the drum when the closure is in position to close the opening.

7. In a machine of the character described, a mixing drum having an inlet opening at one end and an outlet opening at the other end and adapted to be tilted about an axis at its discharge end, a closure plate for the inlet opening, an air pipe extending into the drum through the outlet opening, and a stem on the plate extending into the pipe so that it is actuated by air pressure in the pipe.

8. In a machine of the character described, a mixing drum having an inlet opening, a closure plate for the opening, and two parts, one an air pipe and the other a stem on the plate cooperating with the air pipe so that the plate is actuated by air pressure in the pipe, one of the parts having a port which is covered by the other part when the plate is in position where the opening is open and is open so that air escapes from the pipe

into the drum when the plate is in position to close the opening.

9. In a machine of the character described, a frame, a carriage pivotally mounted in the frame, pneumatic means for swinging the carriage, a mixing drum rotatably mounted in the carriage, the drum having an intake opening and an outlet opening, a stationary pneumatic ejector, a connection between the outlet opening and the ejector, a closure plate for the intake opening, an air pipe extending into the drum through the outlet opening, a hollow stem extending from the plate into the pipe so that the plate is moved to a position where it closes the opening by pressure in the pipe, the stem having a port which is covered by the pipe when the plate is in position where the opening is open and is uncovered to allow air to escape from the pipe into the drum when the plate is in position to close the opening, and a spring arranged in connection with the plate to move it to a position where the opening is open when pressure is released from the pipe.

10. In a machine of the character described, a mixing mechanism adapted to be tilted to discharge material mixed by it, means for supplying air to the mixing mechanism to aid the discharge of material therefrom, a stationary pneumatic ejector adapted to handle material mixed by the mixing mechanism, and a flexible connection between the mixing mechanism and the ejector.

11. In a machine of the character described, a frame, a carrier having one end pivotally connected with the frame, means for swinging the carrier relative to the frame, a mixing drum rotatably mounted in the carrier, the drum having an inlet opening at one end and an outlet opening at the other end and being convergently tapered toward the end having the outlet opening, power means mounted on the carrier for rotating the drum, a closure for the inlet opening, pneumatic means for actuating the closure and adapted to discharge air into the drum when the closure is in position to close the opening, a pneumatic ejector, and a flexible connection between the outlet opening of the drum and the ejector.

In witness that we claim the foregoing we have hereunto subscribed our names this 10th day of Feb., 1922.

HAROLD K. FOX.
GEORGE J. FISHER.
